UNITED STATES PATENT OFFICE.

PETER J. KUTULAN, OF SAN FRANCISCO, CALIFORNIA.

FIRE-ALARM SYSTEM.

1,287,348.

Specification of Letters Patent. Patented Dec. 10, 1918.

Application filed March 7, 1918. Serial No. 220,990.

To all whom it may concern:

Be it known that I, PETER J. KUTULAN, a citizen of the United States, residing at San Francisco, in the county of San Francisco and State of California, have invented certain new and useful Improvements in Fire-Alarm Systems; and I do declare the following to be a full, clear, and exact description of the invention, such as will enable others skilled in the art to which it appertains to make and use the same.

This invention relates to certain new and useful improvements in fire alarm systems.

The primary object of the invention is to provide a fire alarm which is automatically operable when a fire breaks out in a building to notify the fire department of the location of the building and also to sound an alarm to the occupants of such building.

Another object of the invention is to improve upon systems of this nature by the provision of an extremely simple, and inexpensive combination and arrangement of parts and one which will be efficient and reliable in operation, and well adapted to the purpose for which it is designed.

With these and numerous other objects in view, the invention consists of certain novel features of construction and the combination and arrangement of parts as will be herein-after fully described and claimed.

In the accompanying drawings, forming a part of the application and in which similar reference characters designate like parts throughout the several views:—

Figure 1 is a diagrammatic representation of a fire alarm system arranged in accordance with this invention;

Fig. 2 is a diagrammatic representation of a portion of the apparatus used in connection with the system;

Figs. 3 and 4 are views of the opposite sides of the switch and telephone operating wheel;

Fig. 5 is a longitudinal sectional view through the casing of one of the thermostatic switches; and

Fig. 6 is a cross sectional view of the same taken substantially on the plane indicated by the line 6—6 of Fig. 5.

Referring more particularly to the drawings, the letter A designates a four story building on each of the floors b of which is arranged an electric circuit 1 including a number of thermostatic switches 2 arranged in multiple, and an electric bell or gong 3 ar-

ranged in series. The circuits 1 are connected in multiple with the conductors 4 and 5 of an electric circuit which runs to the basement C of the building A, the conductor 4 being connected to one of the terminals of an electric light or sign 6 arranged in front of the building while the conductor 5 is connected to the pole 7 of a double throw two bladed switch 8. The other terminal of the lamp 6 is connected by a conductor 9 to the blade 10 of the switch 8, and the other blade 11 of the latter is connected to one of the line wires 12. The other line wire 13 is connected to the pole 14 of the switch 8.

To the poles 15 and 16 of this switch are connected conductors 17 and 18 respectively, the conductor 17 running to one of the brushes of an electric motor 18 while the conductor 18 is connected to the above mentioned conductor 4 leading to the lamp 6. The other brush of the motor 19 is connected by means of a wire 20 to the relatively fixed contact of a switch 21, the movable member of which is electrically connected with the line wire 13 by a short conductor 22.

Geared to the motor 19 by a suitable train of gears 23 is a shaft 24, one end of which carries a beveled gear 25 which meshes with a beveled pinion 26 carried on the shaft of the turn table 27 of a phonograph. Geared to the shaft 24 by a set of reducing gears 28 is a shaft 29 on which is mounted a wheel 30 having on one side thereof a cam 31 which engages the switch 21 and throws it to opened position, while on the other side of the wheel 30 is a cam groove 32 which engages and operates the switch arm 33 of a telephone 34. The transmitter 35 of the telephone is disposed adjacent preferably in alignment with the horn 36 of the above mentioned phonograph so that the sound produced by the phonograph will be transmitted over the telephone. The undulations on the phonograph record 37 are such that a mechanical voice will be produced explaining that a certain building is on fire.

Each of these thermostatic switches 2 comprises a hollow cylindrical casing 38 which is fastened to the wall or ceiling in any suitable manner, and which is provided over its open or front side with a transparent covering 39. In this casing 38 is mounted a lug 40 to which the movable blade 41 of the switch is pivoted. This blade 41 is normally held out of engagement with the fixed contact 42 of the switch against the tension of

its spring 43 by means of a fuse wire 44, one end of the latter being connected to the blade 41 while the other end is connected to a bar 45 which extends transversely across the 5 casing 38.

The conductors which connect each of the switches 2 to the circuits 1 are connected as is obvious to the lugs 40 and contacts 42 of the switches.

10 Normally, all of the switches 2 are open, the blades 10 and 11 of the switch 8 are in engagement with the poles 7 and 15, the switch 21 is closed, and the telephone switch arm 33 is maintained in raised position by 15 the cam slot 32 so that the circuit through the phone is open. Now should a fire break out in a building the heat thereof will cause the fuse wire 44 of the switch or switches 2 located near the fire to melt and close the 20 respective circuit 1 so that current will pass from the line wire 12 to and through the blade 11 of the switch 8, through the wire 5 to the above mentioned circuit 1, through said circuit, wire 4, lamp 6, wire 9, blade 25 10 of the switch 8, wire 17, motor 19, wire 20, switch 21, and wire 22 to the other line wire 13. Current thus being supplied to the motor 19 will cause the same to revolve and operate the phonograph. The wheel 30 will 30 also be put in motion and the cam groove 32 will pass out of engagement with the telephone switch arm 33, allowing the latter to drop and closing the circuit through the telephone.

35 The reducing gears 28 cause the wheel 30 to rotate very slowly, the table of the phonograph, however, rotating rapidly. The ratio of the gearing is such that the entire message on the record 37 will be reproduced 40 while the wheel 30 is making one revolution. As this wheel revolves, the cam 31 will engage the blade of the switch 21 and the cam groove 32 will engage the telephone switch arm 33 and simultaneously open the 45 switch 21 and raise the arm 33. The circuit being thus broken will stop the rotation of the motor.

If it is desirable to keep the lamp 6 burning so that the fire department which has 50 been automatically summoned can readily ascertain which building the fire is in, the switch 8 is manually swung into the other direction as soon as the motor 19 has stopped. The current will then pass through the line 55 wire 12, blade 11 of the switch 8, wires 18 and 4, lamp 6, wire 9, blade 10 of switch 8 and line wire 13. It is to be understood that the switch 8 is operated by hand.

After the device has been once operated, it 60 is again set by placing a new fuse wire in the switch 2 which sets the apparatus into operation and by closing the switch 21 and throwing the switch 8 so that its blades 10 and 11 engage the poles 7 and 15.

65 From the foregoing description, taken in

connection with the accompanying drawings, the construction, use, and operation of the invention will be readily understood without a more extended explanation.

As various changes may be made without departing from the spirit of this invention it is to be understood that I do not wish to be limited to the construction shown and described other than as claimed.

I claim:

75 1. In a system of the class described, the combination of a circuit, a normally open thermostatic switch, a motor, and a normally closed switch arranged in said circuit, a phonograph operated by said motor, a telephone disposed adjacent said phonograph to transmit the message produced by the latter, and means operated by said motor for throwing said telephone into operation for a predetermined length of time and 80 opening said normally closed switch at the end of said period of time.

2. In a system of the class described, the combination of a normally open thermostatic switch, a motor, and a normally closed 85 switch arranged in said circuit, a phonograph operated by said motor, a telephone disposed adjacent said phonograph to transmit the message produced by the latter, a movable member operated by said motor, 90 means carried by said movable member for throwing said telephone into operation for a predetermined length of time, and means carried by said member for opening said normally closed switch at the end of said 95 100 period of time.

3. In a system of the class described, the combination of a normally open thermostatic switch, a motor, and a normally closed 105 switch arranged in said circuit, a phonograph operated by said motor, a telephone disposed adjacent said phonograph to transmit the message produced by the latter, a rotating member operated by said motor, and cams on said member for throwing said 110 telephone into operation for a predetermined length of time and opening said normally closed switch at the end of said period of time.

4. In a system of the class described, the 115 combination of a normally open thermostatic switch, a motor, and a normally closed switch arranged in said circuit, a phonograph geared to said motor, a telephone disposed adjacent said phonograph to transmit 120 the message produced by the latter, a wheel geared to said motor so that it makes one rotation during the time that the phonograph completely reproduces its message, and means on said wheel for throwing said telephone into operation during said period of time and opening said normally closed switch at the end of said period of time.

5. In a system of the class described, the 125 combination of a circuit including a motor,

- a normally open thermostatic switch, an audible signal, a visual signal, a normally closed switch, and a two-way switch, said two-way switch arranging said signals and
5 said motor in series when in one position and including the visual signal alone in the circuit when in its other position, a phonograph operated by said motor, a telephone disposed adjacent said phonograph to transmit
10 the message produced by the latter, and means operated by said motor for throwing

said telephone into operation for a predetermined length of time and opening said normally closed switch at the end of said period of time.
